UNITED STATES PATENT OFFICE.

SOLOMON H. GOLDBERG, OF CHICAGO, ILLINOIS, ASSIGNOR TO THE HUMP HAIRPIN MANUFACTURING COMPANY, OF CHICAGO, ILLINOIS, A CORPORATION OF WEST VIRGINIA.

TUBE-CUTTING MECHANISM.

1,424,472.

Specification of Letters Patent. Patented Aug. 1, 1922.

Application filed December 14, 1918, Serial No. 266,670. Renewed January 11, 1922. Serial No. 528,563.

To all whom it may concern:

Be it known that I, SOLOMON H. GOLDBERG, a citizen of the United States, residing in the city of Chicago, county of Cook, and State of Illinois, have invented certain new and useful Improvements in Tube-Cutting Mechanisms, of which the following is a specification.

This invention relates to improvements in tube cutting mechanisms and refers more particularly to a device for cutting paper tubes into a plurality of relatively small circular bands.

Among the salient objects of the invention, are to provide a construction in which tubes are fed to a plurality of spaced apart stationary knives and severed into a plurality of small bands of predetermined width; to provide a construction of the above character which is particularly characterized by its ability to cut a maximum number of tubes in a given time; to provide a construction in which the bands are placed on the rods or forms before being fed to the cutting mechanism and which themselves act to form frictional engagement to actuate the feeding mechanism; to provide a construction which can be very economically manufactured, is devoid of any complicated parts and is reliable in operation, and in general to provide an improved construction of the character referred to.

In the drawings:

Fig. 1 is a side elevation of the device.

Fig. 2 is a front end view of the same.

Fig. 3 is an enlarged sectional detail of a cutting and feeding mechanism.

Fig. 4 is an end view of the construction shown in Fig. 3.

Fig. 5 is a sectional plan view on the same scale as Figs. 3 and 4.

Referring to the drawings, 1 designates the main frame member in the upper end of which is removably mounted a box or receptacle 2 to receive the cut tubes or bands. In the lower half of the main frame member is a motor 3 which drives a main shaft 4 through means of pulley belts 5 and 6 and pulleys 7, 8, 9 and 10. The main shaft 4 is mounted in the slides or ways 11 and the journal boxes 12 and in these ways are interposed springs 13; the arrangement being such that the shaft can be forced slightly back in the ways against the action of the springs in the manner hereafter described.

To the shaft 4 is keyed a roller 14 provided in its outer periphery with spaced corrugated ring portions 15 which may be formed at intervals on the roller. The hub 16 of the roller is provided at either end with a boss 17 and in each of these bosses is loosely journaled an annular plate 18. The periphery of each of these plates 18 projects beyond the periphery of the roller as shown at 19. The normal position of these plates are shown in Fig. 3. Each of these plates is provided at its upper edge with a notch 20 which notch 20 normally rests between channel members 21. These channel members 21 are secured to the extension of the main frame and the tubes are fed between the channel members through a chute 22 separated by bracket 23. The tubes are fed to the chute 22 by hand from a table 24 projecting out from the main frame. Pivotally secured as shown at 25, to each channel member, is a link 26 the other end of which is pivoted as shown at 27 to a friction shoe 28, it being understood that there is one of these shoes at either side of the machine. The shoe is normally forced downwardly by means of the springs 29. The under face of each shoe 28 is curved as shown at 30. These shoes are spaced relative to the roller so as to not have frictional engagement therewith but to frictionally engage against the tubes 31 when the latter rests in the notches 20. These tubes 31 after being placed in the chute 22 are loosely mounted on the rods or forms 32. The arrangement is such that the tubes 31 and rods 32 project slightly beyond the periphery of the plates 18.

The plates are tied together so as to rotate in unison by means of the rods 33, 34, 35. Between the rods 34 and 35 is suspended a curved weight 36 which is so arranged that when friction is released from the plates, or in other words when the notched portions of the plates have travelled to the position A shown in dotted lines in Fig. 3, the weight 36 will swing back by gravity and turn the plates to position shown in Fig. 3. The backward swing of the weight is limited by means of a spring supported on stop 37 cooperating with extensions 38 on rod 35. As heretofore stated, the frictional engagement between the shoes 28 and the tubes 31 is such that the plates have a limited travel with the roller. As the tubes 31

travel downwardly, they are severed by spaced stationary knife members 39. These knife members 39 may be similar in construction to a Duplex razor blade and are provided with a slotted portion 40 fitting over the transversely extending rods 41. The blades 39 are separated by the spaced blocks 42. By changing the widths of the blocks, the tubes may be severed into bands of different lengths in an obvious manner. The arrangement is such that the knives cut the tubes without cutting too greatly into the wooden rods. After the tubes have been cut, the rods roll down the delivery arms 43 into the box 2. The tubes are then stripped off of the rods by merely up ending the rods.

The device has been used to cut tubes into narrow bands for holding bundles of hair-pins. Difficulty has been experienced in cutting a sufficient number of bands by means of mechanisms now in use. By means of the present invention, one machine can make several hundred thousand of these bands a day.

I claim as my invention:

1. In a machine for cutting tubes, into bands, the combination with a frame member, of a revolving roller, a carrier loosely mounted relative to the roller and provided with a tube supporting portion, cutting knives, means for forcing the carrier into

frictional engagement with the roller to carry the tubes past the knives and means for returning the carrier to normal position. 35

2. In a machine for cutting tubes into bands, the combination with a frame member, of a revolving roller, a carrier loosely mounted relative to the roller and provided with a tube supporting portion, cutting knives, means for forcing the carrier into frictional engagement with the roller to carry the tubes past the knives and means for returning the carrier to normal position, 45 comprising a weighted portion operatively connected to the carrier.

3. In a machine for cutting tubes into bands, the combination with a frame member, of a carrier loosely mounted thereon 50 and provided with a tube supporting portion, cutting mechanism and means for rocking the carrier to carry the tubes past the knives and means for rocking the carrier back in an opposite position to return it to 55 normal position.

4. In a machine for cutting tubes into bands, the combination with a rocking member slotted to receive the tube to be cut, a frictional member adapted to have cooperative engagement with the tube, cutting mechanism and means for forcing the tubes past said cutting mechanism to sever them. 60

SOLOMON H. GOLDBERG.
